UNITED STATES PATENT OFFICE

LEWIS J. MCSWEENEY, OF DETROIT, MICHIGAN

SHIPPING DEVICE

Application filed August 6, 1931. Serial No. 555,459.

This invention relates to shipping devices and more particularly to a knock-down box or crate, which upon reaching its destination can be easily and quickly disassembled for storage or return to the shipper in compact form for further use.

One of the objects of the invention is to provide a packing case which is simple in design, inexpensive to build and use, and easy to handle, assemble and disassemble.

Another object is to provide a box made up of a number of separable sections or wall units which can be readily fitted together and held in assembled relation without the use of nails or other fastenings which would tend to mutilate or otherwise cause damage to parts, particularly when the box is taken apart.

Additional objects and advantages will become apparent from an inspection of the accompanying drawings when taken in connection with the following description:

In the drawings, Figure 1 is a view showing in perspective the several wall units of a partly assembled box; Figure 2 is a perspective view of the box completely assembled; Figure 3 is a view showing in perspective several units of another form of box partly assembled; and Figure 4 is a perspective view showing the parts of Figure 3 in final assembly.

As will be evident from the drawings, the invention in a preferred but not necessarily the only embodiment thereof contemplates the provision of a series of separable wall sections or sub-assembly units, certain of which carry shouldered seats or other suitable locating or bearing portions for interlocking engagement with co-operative mating bearing portions of other of the units to interlock the several units one with another, and prevent their relative shifting and collapse when brought together, and the use of tensioned bands or hoops surrounding the assembly in different directions to bind the units together and hold them in assembled relation, such tension elements being the sole means of tying the units against separation.

In a crate of this type, the tension bands take practically all of the strain and carry

the load, while the walls serve principally as a protective enclosure for the articles or merchandise to be shipped. As distinguished from conventional shipping boxes made up of a number of boards individually nailed together and which is usually torn apart and destroyed when it is unpacked, the present box being made up of preassembled wall units on all sides can be put together quickly at the point of shipment by simply selecting the proper wall sections, which may be kept on hand in numbers, and placing them about the part or parts to be shipped and then binding the walls by the encircling tie elements, and the box can be just as easily taken apart upon reaching its destination by simply cutting or severing at any point, the encircling hoops, whereupon the wall units are immediately freed for separation, one from another, with no necessity for forcing or prying them apart. The tie bands being inexpensive items may be discarded after a single use, but the wall units not having been mutilated or injured in any fashion, by fastenings, nails, forced separation, or otherwise, may be used over and over again. In the event they are to be returned to the shipper or otherwise transported from place to place or placed in storage for further use they are, of course, packed in disassembled or knocked-down form so as to occupy a minimum of storage space. In knocked-down form, each unit is a flat plate-like part with no projections or other obstructions to interfere with compact stacking.

The case shown in Figures 1 and 2, has six sides or wall units, including a pair of end walls A—A, top and bottom units B—B and two side walls C—C. Each of these units may consist of wooden boards or other suitable material separately assembled into the complete section. Each side unit C—C is shown as comprising three boards 1 extending longitudinally of the box in edge to edge relation, with a pair of cross pieces 2 connecting the boards by nailing or the like and seating within rabbeted portions on opposite ends of the boards so that the exposed surfaces of the cross members lie flush with adjacent surfaces of the longitudinal boards.

As in the case of these side units, the top and bottom wall units B—B are preferably duplicates, each consisting of a number of boards 3, preferably extending longitudinally of the box and held together by cross pieces 4 to which they are nailed, three of such cross pieces being shown in the drawings, one at each end and one at an intermediate point. Overlapping the endmost board 3 on each side is a strip 5, whose outer edge projects beyond the outer edge of the board it overlaps, and provides thereby a shouldered seat to receive an adjacent edge of one of the side wall units. The two end units A—A are also, by preference, identical to each other, and each is shown as consisting of a number of vertical boards 6 nailed side by side to a pair of cross pieces 7 projecting along the top and bottom of the wall. The inner face of the assembled boards is rabbeted along all four edges to provide receiving seats for all four sides of the box, to locate such side walls as well as the end wall itself. The several wall units A—A, B—B and C—C are thus interlocked against any relative shifting movement by reason of the interfitting adjacent edge portions thereof. To hold these wall units against separation, use may be made of a series of encircling hoops or bands 8 of wire or strip stock which encircles the assembly in different directions, each of which may be drawn tightly about the assembly and then secured by any suitable interlock between its ends. Under the hoops where they bend around the box corners, it will be found desirable to employ angle plates 9 to distribute the tensioning stresses and protect the marginal edges of the box walls from injury.

The box above described has been designed and is particularly adaptable for shipping plate glass, although its use is in no way limited. When the box is to be used for shipping plate glass, for example, six wall units are first selected and then the bottom wall unit B is placed flat on the floor or other suitable support and is preferably covered with straw, excelsior or other packing, upon which is rested a series of superposed glass plates, the bulk of which is slightly smaller than the interior dimensions of the box. The side walls C—C and end walls A—A are then brought together in interfitting relation to each other and the lower wall unit B and are encircled by one or more of the hoops 8. Two of such hoops are illustrated in the drawings located respectively near the top and bottom, and each encircling the two side wall and two end wall units. Additional straw packing is then placed about the plate glass to completely fill up the clearance space between the glass and enclosing walls, and the top wall unit B is positioned in interlocking relation with the other wall units, after which additional hoops 8 are passed around the side walls and top and bottom wall units. Any

number of encircling hoops may be employed, depending upon the size of the shipping case and general conditions. For example, one or more additional hoops may be encircled about the top and bottom and end wall units. As thus banded, the box is ready for shipment and may be lifted and carted away, but in such handling the load and strain is taken principally by the banding rather than the wall units, and the wall units serve mainly as a protective casing for the box contents. As heretofore indicated snapping of the hoops at any point of their length permits their removal and the immediate separation of the wall units from each other for access to the box contents, and since there are no anchorage connections between the walls to be broken or torn apart, the walls remain undamaged and in good condition for reuse.

The principle involved may be extended and applied to shipping cases for handling goods and merchandise of various kinds. For example, the invention will be found to be particularly useful for the crating of furniture or like articles having a surface finish, which must be protected against marring or scratching. In this connection it may be mentioned that manufacturers of porcelain coated refrigerators have had considerable difficulty in safe shipment of their product, inasmuch as the porcelain coating tends to crack or chip off whenever any undue strains or stresses are imposed upon the panel carrying such surface finish. Much of the trouble heretofore experienced with the shipment of these refrigerators has been overcome by the use of a crate made in accordance with the present disclosure.

A crate for this purpose is shown in Figures 3 and 4 of the drawings as including a pair of duplicate top and bottom wall units D—D and four side wall units E—E and F—F, those opposite each other being identical and interchangeable. In the case of the side wall units E—E, there is involved a series of vertically extending slats 10 shown as being spaced apart and secured together by cross pieces 11 to which they are nailed. Each of these cross pieces 11 extends laterally beyond the two end slats 10 and the cross pieces adjacent the top and bottom are set inwardly of the ends of the slats to provide a shoulder or bearing portion for an adjacent end wall D—D. The remaining two side units F—F also consist of vertically extending slats 12 nailed to cross pieces 13, but in this case the cross pieces 13 end short of the marginal edges of the outermost slats 12 to form seats which receive the ends of the cross pieces 11 of the adjacent side units E—E to locate the several sides relative to each other. Here again the top and bottom cross pieces 13 end short of the slat ends to receive the adjacent end units D—D. Each top and bottom or opposite end unit D—D is shown as

comprising a rectangular frame made up of spaced sills 14 to which are nailed the cross pieces 15, whose side and ends are spaced inwardly from the sides and ends of the sills thereby providing seats for engagement with the side units. A sheet 16 of veneer, cardboard or the like may be interposed between the cross pieces 15 and sills 14 and close the space within the frame. The sills 14 may according to choice, carry a series of angle members 17 which project beyond the inner face thereof and cooperate with the cross pieces 15 in forming a channel or groove to receive the adjacent ends of the side units E—E and F—F to better locate the same. On the inner side of each sill 14 is secured a pair of blocks 18 in spaced relation to the cross pieces 15 for cooperation therewith to form ways or guides in which are received bars or key members 19 secured to the refrigerator cabinet at its top and bottom. These key members 19 may be nailed to the upper frame of the cabinet, after the top porcelain covered panel has been removed. It may be mentioned that some refrigerators have a removable top panel which facilitates packing. The lower bars 19 may be nailed to the refrigerator frame on the underside thereof or in some cases may be simply held in place by dowels that project into caster stem openings. Encircling hoops 20 are relied upon to hold the several wall units in assembly.

To place the refrigerator cabinet in the casing, the bars 19 are first secured in place and then the cabinet is lowered on the bottom unit D so that the bars or key members fit into the ways provided between the cross pieces 15 and blocks 18. The several side units are then placed about the cabinet in interfitting relation to each other and the lower unit and then the top unit D is dropped into place in interfitting relation with the several side walls and the upper key members 19. The assembly is then ready for banding in the manner before referred to. It should be noted that the use of the angle members 17 eliminates the need for bands around the four side units at the top and bottom, although, of course, additional banding could be used around the sides either with or without the angles. It will be obvious that the crating of a refrigerator cabinet in this fashion eliminates any positive connection between the crate and the cabinet so that the cabinet in effect floats in the crate, and for this reason the porcelain covered panels are freed from the imposition of such stresses as would tend to crack or chip the finish.

I claim:

1. A collapsible returnable shipping case comprising a series of separable wall units, locating means on certain wall units for engagement with adjacent units to prevent inward collapse of the assembly, and tension hoops encircling the assembled units in dif-

ferent directions and being the sole means for holding the respective units against outward separation from one another whereby removal of said elements frees the units for immediate separation. 70

2. A shipping case including a series of separable wall units which include four sides and two ends, each wall providing on its interior a smooth unbroken surface from end to end and each marginal edge of the end units having a rabbeted offset to engage adjacent edges of the side units to locate all the units relative to each other, shoulder portions along opposite edges of two of the side units to engage adjacent edges of the other two of the side units to locate the side units relative to each other, and tension hoops encircling the assembled units, certain of which are in planes at right angles to others and being the sole means for holding the respective wall units against outward separation. 80

3. A shipping case including a series of separable wall units which include four sides and two ends, shoulder portions at each marginal edge of the end units to engage adjacent edges of the side units to locate all the units relative to each other, shoulder portions along opposite edges of two of the side units to engage adjacent edges of the other two of the side units to locate the side units relative to each other, and a series of tension hoops, which include a band encircling the end units and one pair of side units and another band encircling the four side units, said tension hoops serving as the sole means for holding 90 said units against outward separation. 95

4. A shipping case, including a pair of end walls, at least one of which is provided with a way to receive a locating projection on the article to be encased, and a series of side walls 100 extending between said end walls, interfitting location members between adjacent edges of the several walls, and a plurality of tension hoops encircling the assembled walls to maintain the walls in assembled relation, 105 certain of said hoops extending in planes at right angles to other hoops. 110

5. A shipping case including a plurality of casing walls having adjacent edges in unattached abutment, to provide a box-like structure, and a series of bands encircling the box-like structure in planes at right angles to each other to hold the walls against outward separation and being free of any connection with the walls. 115 120

6. A shipping case comprising a series of walls adapted for assembly in an abutting relation which holds the walls against inward collapse while leaving each wall free for independent outward separation, and a series of hoops encircling the assembly in different directions to hold all of said walls against outward separation, said hoops being the sole means for maintaining the assembled relation. 125 130

7. In combination with an article to be shipped, provided with key devices, of a pair of oppositely disposed casing walls having ways to receive said key devices, a series of casing walls enclosing the article with adjacent edges in abutment with each other and with the first mentioned walls to limit inward movement of the walls, and a series of compression bands encircling the assembly and being the sole means to prevent outward separation of the walls, at least one of said bands extending in a plane angular to that of another.
8. A six sided enclosure for protecting a plate glass shipment, including a bottom wall adapted to receive thereon in succession a layer of packing material and the plate glass to be shipped, a pair of side walls and a pair of end walls, each adapted to be brought inwardly into contact with packing beside the glass and into abutting edge to edge relation with the bottom wall, a compression band encircling the side and end walls to prevent their outward separation and hold the packing under pressure, a top wall overlying packing material on the upper side of the glass and abutting at its edges the adjacent edges of the side and end wall, and a compression band encircling the bottom, side and top walls to compress the packing and hold the walls against outward separation, the tension of said bands being the sole means for supporting the load in all directions.

In testimony whereof I affix my signature.
